UNITED STATES PATENT OFFICE.

EMIL A. PAULI, OF CHICAGO, ILLINOIS, ASSIGNOR OF FOUR-FIFTHS TO JOHN HEWITT, ORLANDO S. GAUCH, DAVID J. WILSON, AND CHARLES T. BLACKFORD, OF SAME PLACE.

ACETYLENE-GAS-GENERATING LAMP.

SPECIFICATION forming part of Letters Patent No. 633,609, dated September 26, 1899.

Application filed August 24, 1898. Serial No. 689,398. (No model.)

To all whom it may concern:

Be it known that I, EMIL A. PAULI, a citizen of the United States, residing at Chicago, Illinois, have invented certain new and useful Improvements in Lamps, of which the following is a specification.

This invention is an improvement in self-generating and self-regulating gas-lamps especially designed for the generation and consumption of acetylene gas, and while its general features are applicable to any form of lamp it is shown in the drawings as especially adapted for bicycle-lamps.

The invention is also adapted for use as a stationary apparatus for generating gas for a large number of burners; but its principal advantages are realized when employed as a portable lamp or apparatus.

The objects of the present invention are—

First. To produce an apparatus in which the admission of water to the carbide is automatically controlled and regulated with the utmost nicety by the pressure of gas in the generating-chamber.

Second. To provide an air-cushioning chamber intermediate the generating-chamber and the water-reservoir, which will preserve a substantial equilibrium of the pressure in the generating and water chambers by, on the one hand, preventing any sudden forcible injection of water from the tank into the cushioning-chamber directly affecting the pressure of gas in the generating-chamber by producing a spurt of water into the generating-chamber, and, on the other hand, in case of a sudden or too voluminous generation of gas will permit the water to be immediately forced back by the gas and cut off from the carbide without any water being necessarily forced back into the tank, as is commonly the case in prior constructions. Practically the air in the cushioning-chamber forms a yielding buffer which will cushion the shock of either gas or water suddenly injected or forced back into the said chamber from either or both the tank or generating-chamber. This air-buffer in the cushioning-chamber will also prevent a too profuse accumulation of water between the tank and the generating-chamber. The air-cushioning chamber, moreover, is so constructed that it

will be impossible to fill the same with water no matter in what position the lamp may be placed or turned, so that its beneficial effect will be constantly maintained regardless of the position of the lamp. The advantages 55 of such a cushioning-chamber will be apparent to those at all familiar with the unequal generation of gas from calcium carbide even in the very best and most finely-regulated apparatus heretofore known, and in particular 60 the advantages of the employment of such a buffer or air-cushioning chamber in portable lamps and especially those designed and used for bicycles will be appreciated, because bicycle-lamps are subjected to violent shocks 65 or jerks in all directions, and these shocks at times would force the water, because of its inertia, violently from the tank into the generating-chamber where such chambers are directly connected and even where they are 70 indirectly connected if the connection is maintained full of water, as in the ordinary constructions of such lamps.

Third. Another object of the invention, attained by the employment of this air-cushioning chamber, is to prevent any water running into the carbide-chamber or into the generating-chamber should the lamp be turned to one side or inverted, which is a common defect in most portable lamps heretofore 80 known and sometimes results in serious and dangerous explosions due to the sudden forcible generation of gas, and this is particularly true in lamps where a considerable supply of water is maintained beneath the carbide-holder in such position that it can freely flow into the carbide or generating chamber if the lamp should be inverted or turned on the side. By my invention in case the lamp should be inverted or turned out of position 90 the water will be trapped in the air-cushioning chamber and cannot enter the carbide-chamber because of the peculiar relative arrangement of the generating-chamber, water-tank, and air-cushioning chamber.

Fourth. A further object of the invention is to provide a removable carbide-holder within the generating-chamber and to employ a slotted water-feed tube open at both ends, through which the water can be admitted 95 100

from the bottom upward in a most nicely-graduated manner to the carbid. At the same time the gas in the generating-chamber can act instantaneously upon the water in said tube and through the carbid by back pressure and can immediately cut off the water from the carbid in the holder without necessarily expelling all the water from the generating-chamber.

10 Fifth. Another object is to provide a gas-cooling chamber, wherein the watery and carbonaceous vapors may be separated from the gas prior to its delivery to the burner.

Sixth. Another object of the invention is 15 to facilitate the introduction of the carbid and filling of the water-tank by so constructing the apparatus that the generating-chamber, water-tank, and air-cushioning chamber may together be quickly removed from the 20 other parts of the apparatus and replaced at will without any troublesome manipulation of parts.

Seventh. Further, in portable lamps, and especially bicycle-lamps, lightness is a great 25 desideratum, and it is obvious that the air-cushioning chamber will lessen the weight of the apparatus by exactly the amount of water which it displaces therein, and in any ordinary bicycle-lamp the size of the air-cushion- 30 ing chamber is such that several cubic inches of space is filled with air, which in ordinary apparatus would be continually filled with water. Anything which deducts from the weight of a bicycle-lamp is an advantage.

35 The air-cushion reduces the weight of the lamp, as it does away with a large amount of "dead" water that would have no chance to attack the carbid. In case of extreme pressure of gas in my apparatus the small amount 40 of water in the air-cushioning chamber may be either forced back into the tank or to one side, so that the gas entering the cushion-chamber can escape into the water-tank through the water-feed pipe to the cushion- 45 chamber and thence to the atmosphere through the air-vent of the water-tank.

Other features and advantages of the invention will be hereinafter stated; and the invention consists in the novel combinations 50 and constructions of parts summarized in the claims, and the accompanying drawings illustrate the invention as embodied in a portable or bicycle lamp.

In said drawings, Figure 1 is a side elevation of my improved apparatus embodied in a bicycle-lamp. Fig. 2 is a vertical sectional elevation of the same. Fig. 3 is a transverse section on line 3, Fig. 2; and Fig. 4 is a detail section on line 4, Fig. 1.

60 C' designates a casing adapted to contain the generating parts of the apparatus, and, as shown, it is shaped to represent a lamp-body and is provided at its upper end with a dome-shaped enlargement C, which forms a 65 gas storing and cooling chamber. This casing C' may be provided with any suitable device for connecting it to a support, such as a

bicycle-frame. To the lower end of this casing is attached a short horizontal tube d^3 , 70 communicating with a gas-storing chamber d , by a pipe D and with a short vertical tube d , the upper end of which may be formed into a burner and the lower part of which is pivotally connected to a support for the reflector E, hereinafter referred to. Closely fitting 75 within the cylinder C' is a removable cylinder A, which is divided near its lower end by a transverse partition a into upper and lower compartments. The upper compartment is again divided, preferably, by a vertical tube B into a water tank or reservoir 1 exterior to the tube B and a generating-chamber 2 within the tube B. The space below 80 partition a and the bottom of the cylinder A form an air-cushioning chamber 3. The lower end of cylinder A is closed by a plate A^4 , which forms the bottom of the cushioning-chamber 3, and the lower end of tube B is secured water-tightly to the transverse 85 partition a . Surrounding the lower end of cylinder A is an annular hollow ring A' , which is air-tightly connected to the bottom A^4 and to the cylinder A at a point above the lower end thereof, so that, as shown, it forms an annular air-chamber, which communicates with the cushioning-chamber 3 by 90 small openings a' in the lower edge of cylinder A. In this construction therefore the ring A' forms a virtual continuation and enlargement of the cushioning-chamber 3 and 95 may increase the beneficial effect thereof. The upper ends of cylinder A and tube B may be left open for convenience in supplying water and carbid to the chambers 1 and 2 when the cylinder A is removed from the 100 casing C'; but when inserted the upper ends of cylinder and tube fit closely and hardly 105 against a gasket c' , of rubber or other suitable material, applied to the lower side of the floor c of chamber C, so that there is no communication between the chambers 1 and 2. 110

The cylinder A is removably secured with in the casing C' by means of laterally-projecting studs a^5 on the side of the cylinder A, which are adapted to engage key-slots c^2 115 in a rotatable annulus C^2 , attached to the lower edge of casing C', the operation of which will be readily understood from Figs. 1 and 2. For convenience of construction this annulus C^2 may be a split ring, the ends 120 of which are united by a screw or rivet c^3 after it is adjusted in position.

The locking portions of the key-slots c^2 are 125 preferably upwardly inclined, so that they will force the cylinder and tube tightly upward against the gasket c' .

The cylinder A may be provided with a peripheral recess a^4 to accommodate the pipe D when the latter is arranged inside the casing C', as shown in Figs. 2 and 3. The water-tank is ventilated by means of a short tube d' , extending through the chamber C and establishing communication between chamber 1 and the atmosphere, as shown. The water-

tank 1 also communicates with the cushioning-chamber by means of a short tube a^3 in the bottom of chamber 1, which extends down and only opens into cushioning-chamber 3 5 close to the bottom A⁴ thereof. The cushioning-chamber in turn communicates with the generating-chamber by means of a pipe B², which opens into the cushioning-chamber 3 close to the bottom thereof at its lower end 10 and into the generating-chamber 2 through an opening a^7 in the partition a at its upper end. This pipe B² is provided with a cut-off valve b², which extends through a stuffing-box to the outside of the apparatus. Within the 15 generating-chamber 2 is placed a removable carbid-holder B', which is preferably open at its upper end, so that it can be conveniently filled with carbid, but is closed at its lower end by a bottom b', which has a small opening 20 in it, however, communicating with the lower end of a small vertically-slitted tube b³, the slit b⁴ in which is preferably continuous from top to bottom. The water entering the generating-chamber will have to pass into pipe 25 b³ and through the slit therein before it can enter the carbid. The water in this tube b³ will be consequently subjected to the direct action of the gas in the generating-chamber, and thus the supply of water to the carbid 30 can be automatically regulated by the gas-pressure with the greatest nicety. It will be observed that this tube b³ is open at both ends, and during the action of the apparatus the water supplied is governed solely by the gas- 35 pressure on the water in the slitted tube which is located in the carbid-holder, and gives instantaneous results and the nicest regulation, due to the fact that water can be forced out of the carbid-holder instantaneously even 40 before it is wholly excluded from the generating-chamber and even after it has once been admitted to the carbid-holder. In prior apparatus only the future supply of water is cut off, the water once admitted to the carbid- 45 holder or generating-chamber remaining and acting upon the carbid and continuing to generate gas even after the pressure becomes such as to exclude the further supply of water to the generating-chamber. 50 Operation: The cylinder A, containing the water-tank, generating-chamber, air-cushioning chamber, and the carbid-holder, is removed from the casing. The tank 1 can be filled with water, the valve b² in pipe B² being previously closed. Then the carbid-holder may be removed from the generating-chamber, filled with carbid and replaced therein, and then the cylinder A is replaced 55 and secured within the casing. A small amount of water will flow from the tank into cushioning-chamber 3 until the air trapped therein is compressed sufficiently to prevent further inflow of water, which will occur when a very small amount of water enters the 60 chamber 3, the "head" of water from the tank being small. The amount of water thus primarily admitted into the chamber 3 will

remain practically constant during the operation of the apparatus. If for any cause a surplus amount of water is forced from the tank 70 into the cushioning-chamber 3, the resiliency of the air-cushion will immediately begin to force the surplus water back into the tank until only the normal quantity of water remains in chamber 3. If now valve b² be opened, 75 water will flow from the tank through the cushioning-chamber 3 and pipe B² into the generating-chamber and rise in tube b³ of the holder and attack the carbid through the slot b⁴ therein. Generated gas immediately 80 rises in the chamber 2 and thence escapes into the storage-chamber C through a small opening c in the floor thereof and thence passes through pipe D to the burner d, when it can be ignited and burned. It will be observed that no water can splash into the generating-chamber. The bend in the feed-pipe B² prevents water therein being forced up or down by inertia when the lamp is suddenly raised or lowered, and no matter how much 85 the water may splash in chamber 3 it does not perceptibly affect the feed to the carbid, because the constant pressure of the body of compressed air in said chamber maintains a uniform feed of water through the pipe B². 90 As soon as any oversupply of gas is generated the back pressure of gas in pipe b³ forces the water from the holder and from the carbid therein instantaneously, and if the over-generation is sufficient it may force the water entirely out of the generating-chamber 95 and into the air-cushioning chamber, which forms a yielding buffer between the generating-chamber and the tank, and the shock of any sudden influx of water from the tank or 100 of gas from the generating-chamber into the chamber 3 is expended on and cushioned by the air in said chamber. The primary effect of these abnormal injections of water or gas into the cushioning-chamber is to first additionally compress the air therein, which thereupon immediately begins to force the water back into the tank until equilibrium is restored. This air-cushion relieves the lamp 105 from any undesirable sudden supply of water to the carbid-chamber or flickering of gas due to the sudden raising or lowering of the lamp, as it acts as a spring or cushion and takes up or yields to the inertia of the water in the water-chamber produced by these 110 causes while the water is on the way from the water-chamber to the carbid-chamber and prevents the water in the tank sucking or pounding the gas in and out of the generating-chamber. 115 The air-cushioning chamber is always maintained in the lamp owing to the fact that in the construction of the lamp the tube from the water-chamber admits the water only at the bottom of the air-chamber and the supply of water for the carbid is taken only from the bottom thereof. A body of air is thus 120 always confined in this chamber and can never escape, and the air-cushion is greatly 125 130

increased by the arrangement of an auxiliary cushion in the ring A'.

The slitted tube in the carbid-holder, which is used as a generating-tube to introduce water to the carbid and is open at both ends to permit the free and unrestricted passage of both gas and water, is important in the practical operation of the apparatus, particularly when used as a bicycle-lamp. In this tube the back pressure of gas is utilized to hold back the water. The slit admits exactly the amount of water and at the exact level necessary to begin the generation of gas with the utmost nicety of automatic regulation and supply.

15 The air always confined in chamber 3 is actually and practically an air-cushion between the tank and generating-chamber and is the result of much study and experiment on my part, and in connection with the slitted tube 20 in the generating-chamber I believe solves the problem of the automatic lamp, and the result of the two is to produce in fact a really automatic lamp. I do not claim the idea of regulating the water-supply by the gas-pressure; but I believe that my method and means of doing so as described in the specification 25 is new and is the first practical solution of the problem of producing a literally automatic acetylene-gas lamp.

30 It will further be observed that by my improved construction of lamp the gas-generating parts are so constructed and connected that they are removable, as if in one piece, from the lamp. This is a matter of great 35 convenience to the user of a gas-lamp for any outdoor purposes. By my method of construction one need not remove the lamp from the wheel for the purpose of charging it. The generator can be taken out, the old charge 40 removed, and water and carbide put in place, and the generator replaced in the lamp in little time without disturbing the remainder of the lamp.

Having thus described my invention, what 45 I therefore claim as new, and desire to secure by Letters Patent thereon, is—

1. An acetylene-gas apparatus comprising a tank and a gas-generating chamber in fixed relation to each other, a gas-storing chamber 50 directly connected to the gas-generating chamber and having no connection with the tank, a water-inlet to the generating-chamber, means for permitting water to pass freely between the tank and said water-inlet, a longitudinally-slitted tube in the generating-chamber, communicating at one end with the water-inlet and at the other with a gas-storing chamber, whereby the supply of water to the generating-chamber is controlled and governed 55 by the pressure of gas on the water in such tube.

2. In an acetylene-gas apparatus, the combination of a water-tank, a generating-chamber adapted to contain the carbide having a 60 small water-inlet to the generating-chamber, a gas-storing chamber directly connected to the generating-chamber but having no con-

nection with the tank, a longitudinally-slitted tube within said chamber freely communicating at top with the gas-storing chamber 70 above the carbide and at bottom with the water-inlet to the generating-chamber, and means for admitting the water from the tank to the bottom of said tube; said tube admitting the water to the carbide through the slit 75 at a level predetermined and controlled by the pressure of the gas in the generating-chamber, and the supply of water to the generating-chamber and carbide being controlled and governed by the direct pressure of the gas on 80 the water in such tube without the employment of extraneous regulating devices, substantially as and for the purpose described.

3. In an acetylene-gas generator, the combination of a tank, the generating-chamber, 85 and an air-cushion chamber intermediate the tank and generating-chamber, and through which the water is passed from the tank to said generating-chamber, said air-chamber having such connections with the tank and the generating-chamber that in any position of the lamp it will constantly contain a substantially uniform volume of air forming an air-buffer in said air-chamber adapted to cushion all shocks from sudden violent movements of 90 the lamp or from an abnormal influx of water or gas into said air-chamber from the tank or generating-chamber, substantially as described.

4. In an acetylene-gas lamp, the combination of a fixed supporting-casing, and a removable cylinder or vessel therein divided by interior partitions into a water-chamber, and a carbide-chamber, and means in said cylinder for permitting water to pass from the water-chamber to the carbide-chamber; with means for detaching or attaching said vessel from or to the casing, substantially as described.

5. In an acetylene-gas-generating apparatus, the combination of the water-tank, a generating-chamber having a closed bottom with a small inlet, and means for directing water from the tank to the inlet of said chamber, with a removable holder in said generating-chamber also having a closed bottom, a vertical longitudinally-slitted tube in said holder opening through the bottom thereof, to permit water to enter the holder by rising in said tube and through the slit therein to contact 115 the carbide at a level predetermined by the pressure of the gas in the generating-chamber; said tube also enabling the water-supply to the carbide to be automatically controlled solely by the direct back pressure of gas in 120 said tube upon the water therein, and without extraneous devices.

6. The combination with the water-tank, the generating-chamber and carbide-holder therein, of an air-cushioning chamber located 130 below and extending beneath the said water-chamber and generating-chamber, and receiving water from the former and supplying it to the latter by pipes or passages opening

into the cushioning-chamber only near the bottom thereof, whereby a cushioning-body of confined air is constantly maintained in said chamber in all positions of the lamp, 5 substantially as described.

7. In an acetylene-gas generator, the combination of the water-tank, the generating-chamber, the storing-chamber above and communicating with the generating-chamber and 10 with a burner, the air-cushioning chamber below and extending under both the water-tank and generating-chamber, said air-cushioning chamber communicating with said tank by a single small inlet-passage and with said generating-chamber by a single small inlet-passage, 15 said passages opening into the bottoms of said tank and generating-chamber and communicating with the air-cushioning chamber only near the bottom thereof, said passages being so arranged that a body of air is 20 constantly confined and always maintained in the said cushioning-chamber in all positions of the lamp, substantially as described.

8. In an acetylene-gas generator, the combination of the water-tank, the generating-chamber, and the air-cushioning chamber communicating with said tank and with said generating-chamber and containing a constant confined air-cushion between the tank 25 and generating-chamber; with the supplementary air-chamber communicating with said air-cushioning chamber, for the purpose and substantially as described.

9. In an acetylene-gas generator, the combination of the water-tank, the generating-chamber, the storing-chamber above and communicating with the generating-chamber and with a burner, and the air-cushioning chamber below the water-tank and generating-chamber 30 communicating with said tank and with said generating-chamber, and maintaining a constant confined air-cushion between the tank and generating-chamber; with the annular air-chamber exterior to and surrounding 35 the cushioning-chamber and the lower ends of the tank and generating-chamber and communicating near its bottom with the bottom of the air-cushioning chamber, for the purpose and substantially as described.

50 10. The combination of the water-tank, the generating-chamber, the air-cushioning chamber intermediate and communicating with both said tank and said generating-chamber and containing a constant body of confined 55 air, a removable holder in said generating-chamber having a closed bottom and a slitted tube in said holder opening through the bottom thereof, substantially as and for the purpose described.

60 11. In an acetylene-lamp, the combination of the fixed casing, a cylinder detachably secured within said casing, and the water-tank, the generating-chamber, and the air-cushioning chamber formed within said cylinder, substantially as described, and means for detachably securing said cylinder in the casing, substantially as described.

12. The combination of the fixed casing having a gas-storing chamber in its upper end, and a burner supply-pipe communicating 70 with said chamber; with a cylinder detachably fitted in said casing, and a water-tank, an air-cushioning chamber and a generating-chamber contained within said cylinder; said tank and generating-chamber indirectly communicating through the cushioning-chamber; with means for detachably securing said cylinder within the casing, the upper ends of the water-tank and generating-chamber being closed by the upper end of the casing when 75 the cylinder is secured therein.

13. In an acetylene-lamp, the combination of the fixed casing, open at bottom and closed at top, and the cylinder removably secured in said casing, a tube secured in said cylinder 80 dividing it into a water-tank and a generating-chamber, and a partition in said cylinder forming an air-cushioning chamber in the lower portion thereof, a water pipe or passage connected with said tank and opening into 85 said cushioning-chamber near the bottom thereof, and a water-inlet from said cushioning-chamber into said generating-chamber opening into the cushioning-chamber near the bottom thereof, and means for removably securing said cylinder, with its contained tank, 90 generating-chamber and air-cushioning chamber, in said casing, for the purpose and substantially as described.

14. In an acetylene-lamp, the combination 100 of the fixed casing, open at bottom and closed at top, and the cylinder removably secured in said casing, a tube secured in said cylinder dividing it into a water-tank and a generating-chamber, and a partition in said cylinder 105 forming an air-cushioning chamber in the lower portion thereof, a water pipe or passage connected with said tank and opening into said cushioning-chamber near the bottom thereof, and a water-inlet from said cushioning-chamber into said generating-chamber opening into the cushioning-chamber near the bottom thereof; with a removable carbide-holder in said generating-chamber having a closed bottom, a longitudinally-slitted tube 110 secured in said holder and opening through the bottom thereof into the generating-chamber, and open at the top into the gas-holding portion of said chamber, and means for removably securing said cylinder with its contained tank, generating-chamber and air-cushioning chamber in said casing, for the purpose and substantially as described.

15. In an acetylene-lamp, the combination 115 of the fixed casing, the gas-storing chamber in the top thereof, the cylinder removably secured in said casing, a tube secured in said cylinder dividing it into a water-tank and a generating-chamber, and a water-conduit connecting said tank and generating-chamber 120 near the bottoms thereof; with a removable carbide-holder in said generating-chamber having a closed bottom, a longitudinally-slitted tube secured in said holder and opening

through the bottom thereof into the lower end of the generating-chamber, and open at the top into the upper portion of said chamber; and means for removably securing said cylinder, containing the tank, generating-chamber and carbid-holder, in said casing, for the purpose and substantially as described.

16. In an acetylene-lamp, the combination of the casing, open at bottom and closed at 10 top, and the cylinder secured in said casing, a tube secured in said cylinder dividing it into a water-tank and a generating-chamber, and a partition in said cylinder forming an air-cushioning chamber in the lower portion 15 thereof, a water pipe or passage connected with said tank and opening into said cushioning-chamber near the bottom thereof, and a water-inlet from said cushioning-chamber into said generating-chamber opening into the 20 cushioning-chamber near the bottom thereof, substantially as described.

17. In an acetylene-lamp, the combination of the fixed casing, the cylinder secured in

said casing, a tube secured in said cylinder dividing it into a water-tank and a generating-chamber, and a partition in said cylinder forming an air-cushioning chamber in the lower portion thereof, a water pipe or passage connected with said tank and opening into said cushioning-chamber near the bottom 25 thereof, and a water-inlet from said cushioning-chamber into said generating-chamber opening into the cushioning-chamber near the bottom thereof; with a removable carbid-holder in said generating-chamber having a closed bottom, and a longitudinally-slitted tube secured in said holder and opening through the bottom thereof into the generating-chamber, and open at the top into the gas-holding portion of said chamber, for the purpose and substantially as described. 30 35 40
